UNITED STATES PATENT OFFICE.

WILLIAM HAMILTON MARTIN, OF FLUSHING, NETHERLANDS.

MACHINE FOR FINISHING TURBINE-BLADES AND SIMILAR ARTICLES.

1,381,486.

Specification of Letters Patent. Patented June 14, 1921.

Application filed April 23, 1919. Serial No. 292,008.

To all whom it may concern:

Be it known that I, WILLIAM HAMILTON MARTIN, a subject of the Queen of Holland, residing at Flushing, the Netherlands, have 5 invented Improvements in Machines for Finishing Turbine-Blades and Similar Articles, of which the following is a specification.

This invention has reference to machines 10 for shaping or forming turbine blades and the like from a bar of the proper blade section so as to adapt them for insertion in the grooves of the turbine drum and casing and for attachment of the usual strips or the 15 like.

A machine according to the present invention is adapted to perform the several operations necessary to convert a blade length of 20 blade section bar into a completed blade during a continuous traverse of a work holder.

The machine comprises a bed over which 25 traverses a table provided with means for gripping and holding a length of blade section bar without deforming it and a series 30 of tools or devices which are so arranged as, during the traverse of the table, to face the base end of the blade, to shape that end of the blade to fit the groove by forming dovetail or other notches in it, to shape its other 35 end to engage in the usual strip fitted to each row of blades, and, it may be, to cut the blade length from the bar and drill the blade to receive the usual stiffening wire or wires. Usually, the tools are adjustably 40 secured to the bed and the gripping and holding means have interchangeable gripping dies and are adjustable upon the table to enable different sizes of blades to be dealt with in the same machine.

45 The machine, which can be variously modified, should be heavily built to avoid vibration during working and to thus insure accurate work.

The accompanying drawings illustrate 50 one construction of machine embodying the present improvements,

Figure 1 being an end view,

Fig. 2 a plan,

Fig. 3 a side view with parts omitted, and

55 Fig. 4 a detail view, partly in section and to a larger scale.

In this construction the machine comprises a bed 1 mounted on standards 2 and formed with slides 3 for the table 4 which 55 is traversed by a screw 5 engaging a nut beneath it. Upon the table are two clamp-

ing devices for gripping the blade section bar toward each end of the blade length; these are adjustable transversely of the direction of movement of the table, and each 60 conveniently comprises a jaw-like member 6 secured to the table by the bolts 7 and fitted with fixed and movable gripping dies 8 and 9 which when in gripping position, leave an aperture conforming to the blade 65 section. The movable die may be held in the gripping position by a wedge 10 inserted in a vertical slot formed partly in the rear jaw of the member 8 and partly in the back of the movable die 9 or as shown in the back 70 of an interposed packing block 11 formed with a corresponding tongue 11^a engaging the part slot in the die 9. Toward one side of the bed, in line with the apertures in the clamping dies when the table is in its initial position, is an adjustable screw stop or abutment 75 12 for determining the distance the end of the blade section bar can be pushed through the dies. On the other side of the bed slightly in advance lengthwise of the bed, may 80 be a circular saw indicated by dotted lines at 13, which saw, during the first part of movement of the table, cuts off the blade to the required length. On the same side of the bed as the stop and farther along it than the 85 saw, is an end milling cutter 14 which faces the base of the blade and beyond this cutter are two milling cutters 15 adapted to dovetail or otherwise shape the base portion of the blade to fit the turbine drum or casing 90 groove. Opposite these cutters on the other side of the table is a milling cutter 16 rotating about a vertical axis and shaped to cut away both edge portions of the end of the blade so as to leave a projecting center part 95 which can be passed through the usual strip and riveted over; the cutter may be in the form of a disk with peripheral groove, cutting surfaces being formed on the bottom of the groove, if required, and on the parts 100 at the two sides of it, as shown, or it may be constituted by two cutters.

The two dovetailing milling cutters 15, which conveniently have cutting edges beveled to correspond to the dovetail and rotate 105 about horizontal axes, are fixed upon spindles 15^a (Fig. 4) mounted in bearings 17 carried by opposed standards or brackets 18; the upper and lower bearings 17 are adjustable vertically along the faces of the standards 18 by screws 19. The lower spindle 15^a has a driving pulley 20 or equivalent

fixed directly to it, and the other spindle is driven from it through a pair of gear wheels 21. The end milling cutter 14 is fixed on a spindle 22 that is mounted in one of the standards 18 and is provided with a driving pulley 23. The two standards 18 are adjustable transversely and longitudinally in relation to each other and the whole arrangement permits of the adjustment of the cutter spindles 15^a to suit different sizes of blades while maintaining the proper driving connections. Thus to permit the cutters 15 to be brought nearer together in a vertical direction, the standards 18 are moved a little farther apart in order to allow the gear wheels 21 to mesh at a relatively different angular position, the axis of one cutter being then no longer vertically above the axis of the other cutter as shown in Fig. 4.

20 The milling cutter 16 at the other side of the table has its spindle mounted vertically in an overhanging arm 24 projecting from a standard 25 adjustable transversely across the far end of the bed 1; the spindle is adjustable vertically and carries a driving pulley at its upper end.

25 The milling tools 14, 15 and 16 are driven by belts 26 and 27 and 28 from a drum 29; the circular saw may be similarly driven 30 from the same drum.

35 The table traversing screw 5 may be operated by hand as in the arrangement illustrated, or be power driven, means being provided for varying its speed during the traverse of the table to suit the operation being performed, if desired.

40 At the far end of the bed are a number of transversely adjustable drills 30 for drilling the blades to receive the stiffening wires; these drills which are indicated diagrammatically only may be electrically, pneumatically, or otherwise driven and, as the drills will meet an inclined surface of the blade on which slip might otherwise occur, 45 each drill may be sheathed in a guide the end face of which may be shaped to correspond to the inclined surface of the blade which presses against it, the guide being held up to said surface by a spring which yields 50 as the table advances and drilling progresses.

What I claim is:—

1. A machine for converting a length of turbine blade section bar into a complete blade, comprising a bed, a table reciprocating thereon, a blade holder adjustably mounted upon such table, the said holder being arranged so that the blade travels parallel to itself, rotary cutting means the position of which is fixed relatively to the 55 bed and in relation to which the blade length is initially adjusted in order to be operated upon thereby at one end, and rotary cutting means adjustable in directions parallel to

and transversely of the reciprocating table in order to operate upon the opposite end of 65 the initially adjusted blade whatever its length.

2. A machine for converting a length of turbine blade section bar into a complete blade, comprising a bed, a table reciprocating thereon, means adjustable transversely of the table for gripping and holding the blade length without deforming it and so that it travels parallel to itself, cutting means at one side of the table rotating about 70 a relatively stationary vertical axis in relation to which the blade length is initially adjusted endwise and rotary cutting means at the opposite side of the table adjustable upon the bed in directions parallel to and 75 transversely of the table.

3. A machine for finishing turbine blades according to claim 2 wherein the tools are adjustably secured to the bed and the gripping and holding means have interchangeable gripping dies and are adjustable upon 85 the table to enable different sizes of blades to be dealt with in the same machine.

4. A machine for finishing turbine blades according to claim 2 wherein the gripping and holding means comprise two clamping devices for gripping the blade section bar or blank toward each end, each said device being constituted by a jaw-like member fitted with fixed and movable gripping dies 95 shaped to conform to the blade section and the movable die being held in the gripping position by means such as a wedge.

5. A machine for finishing turbine blades according to claim 2, wherein opposite the 100 initial position of the gripping and holding means is an adjustable stop substantially as and for the purpose specified.

6. A machine for finishing turbine blades according to claim 2 wherein, during the first 105 part of the movements of the table, a circular saw cuts off the blade to the required length from the blade section bar.

7. A machine for finishing turbine blades according to claim 2 wherein an end milling cutter faces the base of the blade and then two milling cutters dovetail or otherwise shape its base portion while another milling cutter shapes its opposite end, substantially as described.

8. A machine for finishing turbine blades according to claim 2 wherein drills for drilling the blades to receive the stiffening wires at the far end of the machine are provided with spring sheaths or guides adapted to 110 check slipping of the drills on the blade face, substantially as described.

Signed at Flushing, Holland, this 1st day of April, 1919.

WILLIAM HAMILTON MARTIN.
